US00D641077S

(12) **United States Design Patent**
Sanders et al.

(10) **Patent No.:** US D641,077 S
(45) **Date of Patent:** ** Jul. 5, 2011

(54) **MEDICAL INJECTOR**

(75) Inventors: **David Sanders**, Warwick (GB); **James Leslie Rhodri Jones**, Maesycrugiau (GB)

(73) Assignee: **Sanofi-Aventis Deutschland GmbH**, Frankfurt (DE)

(**) Term: **14 Years**

(21) Appl. No.: **29/365,832**

(22) Filed: **Jul. 15, 2010**

Related U.S. Application Data

(62) Division of application No. 29/333,748, filed on Mar. 13, 2009, now Pat. No. Des. 621,500.

(51) **LOC (9) Cl.** **24-02**

(52) **U.S. Cl.** **D24/113**

(58) **Field of Classification Search** D24/112-114, D24/133, 186, 104, 130, 127, 152, 144, 146, D24/222, 142; 606/181, 185, 205, 142; 604/232, 604/187, 158, 164.08, 192, 263, 163, 181, 604/184, 198, 227, 186; 433/80; D19/43, D19/50

See application file for complete search history.

(57) **CLAIM**

The ornamental design for the medical injector, as shown and described.

DESCRIPTION

The file of this patent contains at least one photograph executed in color. Copies of this patent with color photographs will be provided by the Office upon request and payment of the necessary fee.

FIG. 1 is a front plan view of the medical injector of our new design;

FIG. 2 is a left side view thereof;

FIG. 3 is a right side view thereof;

FIG. 4 is a rear view thereof;

FIG. 5 is a bottom view thereof; and,

FIG. 6 is a top view thereof.

The colors of the depicted embodiment are as follows:

Body: Pantone 544C (corresponds to flat blue); and,

Actuating Knob: White.
